UNITED STATES PATENT OFFICE.

MAHLON A. UNGER, OF DORMONT, PENNSYLVANIA.

WATER-HEATER.

1,243,901.

Specification of Letters Patent. Patented Oct. 23, 1917.

Application filed January 20, 1916. Serial No. 73,193.

To all whom it may concern:

Be it known that I, MAHLON A. UNGER, a citizen of the United States, residing at Dormont, in the county of Allegheny and 5 State of Pennsylvania, have invented certain new and useful Improvements in Water-Heaters, of which the following is a specification.

My invention consists of an improvement 10 in water heaters, and has for its object to provide a heater in which the products of combustion of the fuel will be utilized to the fullest extent and with resulting economy to quickly heat a limited volume of water.

15 The heater comprises a boiler having a central fuel combustion chamber within an inner shell and an outer shell providing therewith an intervening annular water containing and circulating space, transverse 20 hollow separated grate bars in circulating communication with the main water space, a lower burner within a laterally enlarged furnace chamber below the grate bars and the annular water chamber, an outer shell, 25 and various other features of detail construction as hereinafter more fully described.

Referring to the drawings:

Figure 1 is a central vertical sectional view through the complete furnace.

Fig. 2 is a transverse sectional view indicated by the line II. II. of Fig. 1.

Fig. 3 is a partial vertical sectional view on the line III. III. of Fig. 1.

35 Fig. 4 is a plan view of the damper.

Fig. 5 is a plan view of the burner.

Fig. 6 is a vertical sectional view showing a modified construction.

Fig. 7 is a transverse sectional view on the 40 line VII. VII. of Fig. 6.

The heater as a whole is mounted on a supporting base 2 of suitable construction, as a circular cast plate, having pedestals 3 adapted to maintain it upwardly above the 45 floor with ample intervening space. The boiler portion consists of an outer shell 4 and an inner shell 5 providing an intervening water cavity or chamber 6, the outer and inner shells being connected by a bottom 50 wall 7, preferably sloping downwardly toward the outer shell, as shown. By this means an ample burner chamber 8 is provided, in which is located the burner 9 having a series of numerous jet openings across 55 its upper face, as shown in Fig. 5.

Immediately above the burner chamber is

a series of transverse hollow supporting grate bars 10 adapted to support the mass of refractory material 11 through which the gases of combustion circulate from the 60 burner. The hollow bars 10 are separated from each other by intervening slot-like spaces 12 through which the gases pass, and the outermost jet openings are located beneath the bottom sloping wall 7, so that the 65 flame impinges thereon, and is directed inwardly and upwardly through the slots 12 toward the refractory material 11. Said material is supported by the hollow bars 10, and these are of sufficient size in cross section to contain a good body of water.

A supply pipe 14 leads to the bottom portion of chamber 6 by connection with the outer shell 4, and a delivery pipe 15 leads from the upper portion of the water chamber 75 to any desired point of use, as a heat radiator or bath room faucet.

The cold water passes inwardly or through the hollow bars 10 from the lower portion of the main chamber 6 and from the upper 80 portion of the bars back into the chamber and upwardly therethrough, as indicated in Fig. 3, becoming highly heated by exposure to the heat of combustion from the burner underneath and between the sides of the hollow bars, in slots 10, and by radiation of the heat from the refractory filling 11. Initially, the water is heated by the jets below the bottom wall 7, and underneath the grate bars, and the heating action increases toward the top.

An outer shell 16 is supported on the base 2 and extends upwardly around the boiler to the top, with an intervening space 17, having a central off-take pipe 18 for the 95 burnt gases which may have a suitable damper, if desired.

Between the outer shell 16 and the top and upper portion of the boiler, is a baffling shell 19 providing for return downward and 100 outer upward circulation, thereby fully utilizing all the remaining heat units, so that the waste of heat is reduced to a minimum.

Below the burner chamber I provide a 105 movable damper plate 20 having openings 21 adapted to register with similar openings in a stationary plate 22 mounted on an annular supporting flange 23 of the base. Damper plate 20 has a handle 24 so that 110 it may be set to supply the desired quantity of air at all times.

Suitable doors 25, 26, may also be provided in the outer shell 16 and also in the lower extension 4' of shell 4 whereby to provide access to burner 9 for lighting, etc., 5 and it will be understood that these details and other necessary or suitable elements will be provided, of proper size and proportions, to suit the other conditions and requirements of the entire installation.

- 10 In Figs. 6 and 7, I show a modified construction in which the series of hollow supporting bars 10^a are depressed at the middle, sloping upwardly at each outer portion. By this construction the circulation 15 of the water is facilitated, the partly heated water at the upper portion of each hollow bar, at each side of its middle, passing upwardly and outwardly to the main annular chamber 6^a, as is the natural tendency.
- 20 For the purpose of baffling the flames of combustion, I may use a circular or disk-shaped baffle plate 27 mounted above the hollow bars 10^a by any suitable support, and with a surrounding annular space 28 by 25 which the flames are forced directly through the outer portion of the refractory filling, and against the inner boiler wall.

With either construction, the full effects of the fuel in combustion are utilized to the 30 highest degree. The contained water is subjected to exposure to the heat throughout the entire course of circulation of the gases, and as a result the comparatively thin annular body of water is very quickly 35 heated to a high degree, with a minimum of fuel.

The advantages of the invention will be readily understood and appreciated by all those familiar with the general class of

water heaters. It is comparatively simple 40 in construction, highly efficient and economical in operation, and will continuously operate to furnish an ample supply of heated water of any desired degree of temperature, depending on the speed of circulation and 45 amount of fuel supply.

The invention may be variously changed by the skilled mechanic in different features or details, but all such are to be considered as within the scope of the following 50 claim.

What I claim is:

In a water heater, the combination of a cylindrical open center casing comprising an inner and an outer concentric shell, a 55 top connecting wall and a bottom outwardly flaring connecting wall therefor, thereby providing an intervening annular water containing cavity, a water inlet and water outlet pipe connected with said cavity, a 60 fuel burner located beneath said water cavity, a lower transverse closure below the burner having means for admitting a variable air supply, a compound inner and outer shell providing for a tortuous circulation of the gases of combustion, said outer shell having an outlet flue, said inner shell 65 extending downwardly a substantial distance around and spaced from said cylindrical casing, and said inner shell being 70 spaced from and supported by said outer shell.

In testimony whereof I hereunto affix my signature in the presence of two witnesses.

MAHLON A. UNGER.
